US00D640925S

(12) United States Design Patent
Rodriguez et al.

(10) Patent No.: US D640,925 S
(45) Date of Patent: * Jul. 5, 2011

(54) COSMETIC CONTAINER

(75) Inventors: Yamilca Del Carmen Rodriguez, Cincinnati, OH (US); Jacqueline Ann Daniels, Hamilton, OH (US); Norman Henry Tiilikka, West Chester, OH (US); Brian Joseph Sullivan, Milford, OH (US)

(73) Assignee: The Procter & Gamble Company, Cincinnati, OH (US)

() Term: 14 Years

(21) Appl. No.: 29/338,394

(22) Filed: Jun. 10, 2009

(51) LOC (9) Cl. 09-01

(52) U.S. Cl. D9/529; D9/454; D9/558; D28/76

(58) Field of Classification Search D9/435, D9/454, 500, 503, 504, 516, 517, 519, 529, D9/549, 554, 558, 572, 573, 574, 434, 445, D9/530, 537-539, 545, 550, 551, 552; D28/73, D28/91, 76-79, 82; 215/381-385, 379; 220/660, 220/662, 669-674, 675, 677, 680; 206/581, 206/823; 132/293

(57) CLAIM

The ornamental design for a cosmetic container, as shown and described.

DESCRIPTION

FIG. 1 is a perspective view of a cosmetic container showing our new design;

FIG. 2 is front elevation view of FIG. 1,

FIG. 3 is a side elevation view of FIG. 1,

FIG. 4 is a top plan view of FIG. 1; and,

FIG. 5 is a bottom plan view of FIG. 1.

Sides not shown form no part of the claimed design.

1 Claim, 3 Drawing Sheets
